HYDRAULIC VALVE OPERATING
MECHANISM

Lorraine L. Manly, Staunton, Va.

Application May 22, 1946, Serial No. 671,474

6 Claims. (Cl. 123—90)

1

This invention relates generally to valve operating mechanism and pertains particularly to improvements in mechanism for operating poppet valves and more particularly valves of the type used in internal combustion engines.

The present invention has for its object to provide a new and novel means of actuating poppet valves whereby back lash is eliminated and proper valve adjustment is automatically accomplished.

Another object of the invention is to provide an improved poppet valve operating mechanism by means of which the usual valve noises are materially reduced and the expansion or spreading of the end of the valve stem, which in known valve operating mechanisms results from the hammering of the push rod, is eliminated.

Other objects and advantages of the present invention are to provide an improved poppet valve operating mechanism whereby the raising of the valve to full opening is accelerated; the valve remains at fully opened position for a greater length of time; movement of the valve from fully opened position to fully closed position is almost instantaneous whereby there is obtained a freer movement of gases through the valve ports with consequent improved engine performance; hammering of the valve upon its seat is materially reduced by reason of hydraulic cushioning, and the usual cams, cam followers and rollers are eliminated.

The invention will be best understood from a consideration of the following detailed description taken in connection with the accompanying drawings forming a part of the specification, with the understanding, however, that the invention is not confined to a strict conformity with the showing of the drawings but may be changed or modified so long as such changes or modifications mark no material departure from the salient features of the invention as expressed in the appended claims.

In the drawings:

Figure 1 shows a portion of a poppet valve cage and an adjacent cylinder in section, the valve and valve operating mechanism constructed in accordance with the present invention being shown in elevation therein with the valve closed.

Figure 2 is a view corresponding to Figure 1 with parts of the valve operating mechanism in longitudinal section and the valve in opened position and on the point of release for closing.

Figure 3 is a longitudinal sectional view through a portion of the upper part of the valve actuating mechanism with the entire unit rotated through ninety degrees.

2

Figure 4 is a view illustrating the application of the invention to a valve of the overhead type.

Referring now more particularly to the drawings reference will first be had to Figures 1, 2 and 3 wherein the invention is shown as applied to the usual poppet valve as employed in the L-type of motor. In the several figures a portion only of the engine body or block is shown, the same being generally designated 10 and a part of a cylinder being shown and designated 10'. The numeral 11 generally designates the valve cage of an engine of the character stated.

In accordance with the present invention there is provided an operating shaft which is generally designated 12 and upon which is mounted for each valve, an eccentric 13.

Circling the eccentric 13 is the eccentric strap 14 with which is integrally connected the eccentric push rod 15. The upper end of this rod is formed to provide the bearing 16 and there is formed longitudinally through the length of the rod 15, the fluid passage 17, the lower end of which is closed at all times by the eccentric 13 with the exception of the short period when the high point of the eccentric is passing the end of the passage at which time the lower end of the passage 17 will have in registry therewith the short radial bore 18 which is formed in and opens through the peripheral face of the eccentric and which discharges laterally through the port 19 in the manner hereinafter described.

The numeral 20 designates the push rod which at its lower end is provided with the right angle extension 21 which engages in the bearing 16 of the eccentric rod to form a pivotal connection with the eccentric rod. The push rod 20 is provided with the axial passage 22 which opens through the upper end of the rod and which at the lower end extends into the right angular extension 21, communicating with the port 23 which in turn communicates with the upper end of the passage 17 as shown in Figure 3.

The push rod 20 is snugly and slidably positioned or mounted in the cylinder 24 which is formed as an integral part of the engine block as shown. The upper portion of the cylinder 24 has leading thereto the fluid inlet nipple 25 with which is connected an end of a pipe 26 through which oil is supplied, in the manner hereinafter described, to the mechanism, under lower pressure. As shown, the inlet from the nipple 25 is so positioned that when the push rod 20 is in its lowermost position it will uncover the oil inlet port and when it is in its uppermost position as shown in Figure 2 it completely closes or seals off this inlet.

The upper end of the push rod cylinder 24 has secured therein and is partly closed by the upwardly opening cup 27 which is of cylindrical form and has a portion of its length lying within the cylinder and a portion extending beyond the upper end of the cylinder as shown. The lower part or bottom of the cup 27 has formed therein the relatively small aperture 28 while the side wall, within the cylinder 24, has a larger opening or lateral port 29 formed therethrough and outside the cylinder 24 a second port is formed in the cup wall as indicated at 30. Thus it will be seen that the ports 28 and 29 of the cup 27 communicate entirely with the inside of the push rod cylinder while the single port 30 communicates with the interior of the valve cage, wholly outside the cylinder 24.

The numeral 31 designates the valve stem guide through which slidably extends the stem 32 of the valve 33 which when fully closed rests upon the seat 34.

Surrounding the valve stem 32 and bearing at one end against the lower end of the guide 31, is the valve actuating spring 35, the lower end of which rests upon the spring stop 36 which is secured to the stem inwardly of the lower or free end thereof.

As shown the portion of the valve stem which extends beyond the spring stop 36 extends into and has snug engagement with the inner wall of the cup 27 and when the valve is in fully closed position, as shown in Figure 1, the end of the stem extends into the cup sufficiently to close the port 29 and when the valve is fully opened, as shown in Figure 2, the end of the stem rises to a sufficient extent to uncover the port 30.

In operation when the eccentric 13 revolves the eccentric rod 15 and push rod 20 are withdrawn to the point where the push rod uncovers the oil inlet for the pipe 26 as shown in Figure 1. At this time the radial passage 18 of the eccentric has passed entirely out of communication with the bore 17 of the eccentric rod and the peripheral surface of eccentric acts as a closure for the bore 17.

Oil under low pressure is introduced by way of the pipe 26 into the upper end of the cylinder 24 above the push rod 20 completely filling the passages or bores 17 and 22 as well as the upper part of the cylinder 24 and the space in the cup 27 beneath the valve stem 32. As the eccentric continues to revolve the push rod 20 will be forced upwardly shutting off the inlet from the pipe 26. During this part of the cycle, no motion is imparted to the valve stem because surplus oil flows freely backward through the oil supply pipe 26. When the push rod 20 rises sufficiently to completely close the inlet nipple port, the oil in the bores or passages 17 and 22 and in the upper part of the cylinder 24 and the lower part of the cup 27 will be trapped. At this point the oil pressure will instantaneously rise to a point sufficiently high to cause a small quantity of oil to flow through the port 28, lifting the valve stem 32 and the valve and thus separating the valve from its seat.

When the lower end of the valve stem 32 has risen above the port 29, oil will flow freely from the cylinder 24 into the cup 27 and, because of the relative differences in diameter of the bore of the cylinder and cup, the valve stem will rise very rapidly until the lower extension of the stem clears the lower part of the discharge port 30. Surplus oil then is ejected through the port 30 and, there being no further upward impulse, the valve stem dwells in this position.

The eccentric continues to revolve to the position shown in Figure 2 where the radial passage or bore 18 of the eccentric comes into registry with the bore 17, full registration between these bores being accomplished at the high point position of the eccentric. When these positions of the parts are reached there is no obstruction to the free return of oil through the system into the engine crank case by means of the bore 18 and the port 19. Under the impulse of the valve spring 35 the valve stem and valve will be driven downward until the lower end of the valve stem has passed beyond the port 29. The valve stem is of such length that at this instant the valve is almost closed upon its seat. After the valve stem 32 completely masks the port 29 the remainder of the oil trapped in the bottom of the cup 27 is discharged into the cylinder 24 through the relatively small port 28. This port is of suitably small diameter so that it affords a check to the escape of oil, causing the valve stem to decelerate in its downward movement, thereby easing the valve 33 onto its seat and preventing the hammering that would occur if the valve were free to seat under the unimpeded force of the spring 35.

In Figure 4 the valve operating mechanism is shown in slightly modified form for the actuation of a valve of the overhead type. In the construction here shown the push rod cylinder is designated 24a and is extended above the top of the engine head 37 and it is then continued at right angles as indicated at 38 to terminate above the valve stem guide 31a. In the terminal portion 38 is fitted the downwardly opening cylindrical cup 27a in which slidably extends the end of the valve stem 32a.

The cup 27a is provided with the small bottom bore 28a and with the side ports 29a and 30a which correspond respectively with the ports 29 and 30.

The push rod which works in the cylinder 24a and the oil inlet port which the rod uncovers when it is in its lowermost position are respectively designated 20a and 26a.

The lower end of the push rod in this modification is not shown as it will be understood that this is the same as the structure shown in Figures 1 and 2 and it will also be readily understood that the operation in connection with the modified arrangement for the actuation of the overhead type valve is the same as set forth in connection with the description of the operation of the device for the L-type motor structure.

From the foregoing it will be readily apparent that with the operating mechanism herein disclosed smooth operation of the entire valve mechanism will be had and the life of the parts will be materially increased.

While one design of eccentric, eccentric strap, eccentric rod, push pin and wrist pin have been illustrated and described it is to be understood that I do not wish to be limited to this specific construction and arrangement of these parts except insofar as is determined by the appended claims.

The cyclic bleeding of the system through port 30 frees the system of gas bubbles once during each operation of the valve, thereby preventing malfunctioning of the system because of the compression of entrained or accumulated air or vapor bubbles.

While the common axis of the valve stem 32 and the cup 27 at the common axis of the push rod 20 and the cylinder 24 have been illustrated

as being the same in Figures 1 to 3, such common axes bear no significant relationship to each other. This characteristic permits the valve to be mounted at any desired angle without in any way interfering with the operation of the mechanism.

I claim:

1. Operating mechanism for a valve of the poppet type including a disk head and valve stem connected at one end to the head, comprising a piston cylinder, a piston extending in one end of the cylinder, means for reciprocating the piston in the cylinder, means connected with the other end of the cylinder forming a receptacle into which the other end of the valve stem is slidably received, a relatively small inlet port forming a communicating passage between the cylinder and said receptacle, an outlet port leading from the receptacle outside the cylinder, the outlet port being uncovered by the valve stem when the valve is in fully opened position, resilient means normally urging the valve to closed position, means for introducing fluid into the cylinder between the piston and said receptacle when the piston is at the limit of its movement outwardly, and means for instantly relieving pressure upon the fluid in the cylinder when the piston is at the limit of its movement inwardly.

2. Operating mechanism for a valve of the poppet type having a stem supported for reciprocatory movement, comprising a relatively long fluid cylinder arranged coaxially with the stem, means forming a receptacle coaxially in one end of the cylinder into which the adjacent end of the stem is slidably received, said receptacle having a relatively small port in its inner end and a relatively large port through one side and opening from the cylinder into the receptacle, the receptacle further having an outlet port opening from the receptacle to the exterior of the cylinder, said stem functioning to uncover said outlet port when the valve is fully opened, resilient means normally urging movement of the valve stem to valve closed position, said stem functioning to close the side wall port of the receptacle prior to full closing of the valve under the action of said resilient means, a piston reciprocable in said cylinder, means for introducing fluid into the cylinder between the piston and the receptacle when the piston is in fully retracted position in the cylinder, and means for relieving the pressure of the fluid in the cylinder when the piston is in fully advanced position therein.

3. A valve actuating mechanism of the character stated in claim 2, with a crank member pivotally connected with the piston, eccentric means connected with the crank for imparting reciprocatory movement to the piston, said piston having a fluid bore longitudinally therethrough, and the said means for relieving the fluid pressure in the cylinder being constructed and arranged to open said bore for the outflow of fluid therethrough from the cylinder.

4. A valve actuating mechanism of the character stated in claim 2, with a piston operating shaft, an eccentric secured to the shaft, an eccen-

tric strap encircling the eccentric and having a crank arm integral therewith, said piston at its outer end being formed to provide a wrist pin and said crank arm being formed to provide a bearing receiving the wrist pin, the said means for relieving fluid pressure in the cylinder at the limit of inward movement of the piston comprising a conduit formed through the piston and through the crank arm and opening upon the the inner side of the eccentric strap, and an exhaust passage formed radially in the eccentric and opening at one end through the peripheral surface thereof for intermittent registry with said bore and opening at its other end through the side of the eccentric.

5. A valve operating mechanism comprising in combination with a valve and valve stem, a receptacle into which the end of the stem is slidably received, yieldable means normally urging the valve and stem to valve closed position and the extension of the said end of the stem into the receptacle, a fluid inlet and a fluid outlet for the receptacle, a fluid conductor leading to said inlet, the fluid outlet being positioned to be uncovered by the valve stem when the valve is in fully opened position, a reciprocable injector working in said conductor for forcing fluid under pressure from the conductor into said fluid inlet, means for introducing fluid into the conductor for compression by the injector, an exhaust passage leading through the injector and having one end in constant communication with said fluid conductor, and means for opening said exhaust passage when the injector is in a position in the conductor in which the fluid is under high compression.

6. A valve operating mechanism in combination with a valve and valve stem, a receptacle having an open end into which the end of the stem is snugly slidably received to function as a piston in the receptacle, yieldable means normally urging the valve and stem to valve closed position and the extension of the said end of the stem into the receptacle, a fluid inlet and a fluid outlet for the receptacle, a fluid chamber in communication with said receptacle inlet, the fluid outlet being positioned to be uncovered by the valve stem when the valve is in fully opened position, means for forcing fluid under high pressure from said chamber into the receptacle through the receptacle inlet, an exhaust passage for said chamber, and means operating to open the exhaust passage while the fluid is under high pressure in the chamber, to release such pressure.
